C. D. MCKENNEY

LUGGAGE HOLDER

Filed Aug. 13, 1923

Fig. 2.

Inventor
C. D. MCKENNEY

By Watson E. Coleman

Attorney

UNITED STATES PATENT OFFICE.

CHARLES D. MCKENNEY, OF PETERSBURG, VIRGINIA, ASSIGNOR TO THE SEWARD TRUNK AND BAG COMPANY, OF PETERSBURG, VIRGINIA, A CORPORATION OF VIRGINIA.

LUGGAGE HOLDER.

Application filed August 18, 1923. Serial No. 657,000.

To all whom it may concern:

Be it known that I, CHARLES D. MCKENNEY, a citizen of the United States, residing at Petersburg, in the county of Dinwiddie 5 and State of Virginia, have invented certain new and useful Improvements in Luggage Holders, of which the following is a specification, reference being had to the accompanying drawings.

10 This invention relates to certain improvements in luggage holders and has relation more particularly to a device of this general character especially designed and adapted for use in connection with the running board of an automobile to maintain a trunk or the like thereon and it is an object of the invention to provide a device of this general character having novel and improved means for engagement with the 15 trunk or the like.

The invention consists in the details of construction and in the combination and arrangement of the several parts of my improved luggage holder whereby certain important advantages are attained and the 20 device rendered simpler, less expensive and otherwise more convenient and advantageous for use, as will be hereinafter more fully set forth.

25 30 The novel features of my invention will hereinafter be definitely claimed.

In order that my invention may be the better understood, I will now proceed to describe the same with reference to the accompanying drawings, wherein:

35 Figure 1 is a view in perspective illustrating a luggage holder constructed in accordance with an embodiment of my invention and in applied position;

40 Figure 2 is an enlarged fragmentary view partly in elevation illustrating in detail the features of my improved holder as herein disclosed;

45 Figure 3 is a view in perspective of one of my improved holders unapplied with parts in section.

As disclosed in the accompanying drawings, B denotes the running board of an automobile and upon which is adapted to be rested a trunk T, said trunk being provided in one of its side walls adjacent its opposite ends with the plates 1, each provided with a socket 2. The plates 1 are positioned at substantially the transverse 50 center of the side walls of the trunk.

Engaged with the running board B and coacting with the opposite end portions of the trunk T are the holders H. These holders are of duplicate construction and a description of one is therefore believed to be sufficient for the purposes of disclosure.

Each of the holders H comprises an elongated rigid member or strap 3 adapted to be disposed transversely of the board B and which has its opposite end portions outwardly offset as at 4 to provide shelves upon which an end portion of the trunk T is adapted to directly rest. The portions 4 terminate in the upstanding flanges 5 which overlie the side faces of the applied trunk. Secured to the central portion of each of the members or straps 3 is an end portion of a rigid arm 6, said arm extending outwardly with respect to the member or strap 3 and provided in its free end portion with an opening 7.

A rod R has one end portion disposed through the opening 7 and also through the running board B, said rod R being provided with an outstanding annular shoulder 8 which engages the arm 6. A nut 10 is threaded upon the lower portion of the rod R and engages the running board B from below whereby the rod R is held in a vertical position upon the board B and the member or strap 3 also effectively secured to the board B.

C denotes a clamp member having one end portion returned as at 11, said returned portion and the body proper of the member C being provided with aligned openings 12 through which the rod R is freely disposed whereby the clamp member C may be readily moved lengthwise of the rod R. The clamp member C is of a length to overlie the end portion of the applied trunk T adjacent to the rod R and is provided with a depending lug 14 herein disclosed as in the form of a truncated cone which is adapted to be received within the socket 2 of the adjacent plate 1. A wing nut 15 is threaded upon the rod R above the clamp member C and by requisite turning movement of the wind nut 15, the clamp member C is caused to have proper engagement with the upper portion of the trunk T whereby the same is effectively held upon the running board B.

Before the trunk T is mounted upon the board B for transit, the same is preferably enclosed or encased within a suitable cover- 100 105 110

ing or jacket 16 to prevent dust or the like having ingress within the trunk.

From the foregoing description it is thought to be obvious that a luggage holder 5 constructed in accordance with my invention is particularly well adapted for use by reason of the convenience and facility with which it may be assembled and operated, and it will also be obvious that my invention 10 is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim—

1. A device of the class described comprising, in combination, a rod, means for connecting an end portion thereof to the running board of a vehicle, a member adapted to be rested upon said running board and disposed transversely thereof, an outstanding arm carried by the central portion of the member, the rod extending through said arm, said rod having a shoulder coacting with said arm whereby the rod, when in applied position, maintains the member 30 upon the running board.
2. In combination with the running board of a vehicle and a trunk having a socket in one of its walls, a post secured to the running board and extending upwardly 35 therefrom, a clamping member loosely mounted upon the post, said clamping member having a lug to engage within the socket of the trunk, and means for maintaining the clamping member in operative engagement 40 with the trunk.
3. In combination with the running board of a vehicle and a trunk having a socket in one of its walls, a post secured to the running board and extending upwardly therefrom, a clamping member loosely mounted upon the post, said clamping member having a lug to engage within the socket of the

trunk, and means carried by the post and coacting with the clamping member to maintain the clamping member in working engagement with the trunk. 50

4. A device of the class described comprising, in combination, a rod, means for connecting an end portion thereof to the running board of a vehicle, a member adapted to rest upon said running board and disposed transversely thereof, the rod extending through said member, said rod having a shoulder coacting with said member whereby the rod, when in applied position, maintains the member upon the running board. 55

5. In combination with the running board of a vehicle, a trunk having a socket in one of its walls, a post secured to the running board, a clamping member mounted upon the post and having movement lengthwise of the post, said clamping member engaging within the socket of the trunk, and means for maintaining the clamping member in 60 operative engagement with the trunk. 65

6. In combination with the running board of a vehicle, a trunk adapted to be positioned upon the running board, a post secured to the running board, a clamping member mounted upon the post, said clamping member and a wall of the trunk having coacting means interlocking when the clamping member is in operative engagement with the trunk. 70 75

7. In combination with the running board of a vehicle, a trunk adapted to be positioned upon the running board, a post secured to the running board, a clamping member mounted upon the post, said clamping member and a wall of the trunk having coacting means interlocking when the clamping member is in operative engagement with the trunk, said interlocking means comprising a lug and socket. 80 85

In testimony whereof I hereunto affix my signature.

CHARLES D. MCKENNEY.
